UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

PNEUMATIC WEFT DETECTOR FOR LOOMS.

Application filed September 26, 1925. Serial No. 58,708.

This invention relates to pneumatic weft detectors for weft replenishing looms and it is the general object of the invention to provide such a detector employing a blast of air 5 to be directed against the yarn but prevented from actuating a controller so long as sufficient yarn is present.

On very fine yarn such as silk it is found that the supply of weft lasts for so long a 10 time that any of the usual types of detectors which strike the yarn will abrade the latter with resulting breakages. In co-pending application, Serial No. 57,916 there is shown a pneumatic feeler employing a blast of air 15 cooperating with a bobbin having a slot therethrough which is in alignment with the air projector and the indicating controller. In said application it is necessary to provide means for placing the bobbin with the 20 slot horizontal, a condition which requires employment of additional mechanism in connection with the transerrer arm.

It is a further object of my invention to obviate the need of special transfer mechanism by employing a weft detector of the 25 general type set forth in said application with a bobbin having perforations therein so arranged that it may be placed in the shuttle in any angular position, sufficient air 30 passing through one or more of the openings to actuate the controller.

With these and other objects in view which will appear as the description proceeds my invention resides in the combination and arrangement of parts hereinafter 35 described and set forth in the claims.

In the accompanying drawings wherein a convenient embodiment of my invention is shown,

Fig. 1 is a top plan view of a detector made according to my present invention, showing the same associated with a shuttle having portions in section,

Figs. 2 and 3 are vertical sections on lines 45 2-2 and 3-3, respectively, of Fig. 1,

Fig. 4 is a view similar to Fig. 2 but showing the parts moved to indicating position,

Fig. 5 is an enlarged transverse section through a bobbin associated with my detector, and

Fig. 6 is a diagrammatic development of the surface of the bobbin.

Referring more particularly to the draw-

ings it will be seen that I have provided a lay 10 which moves back and forth in a loom frame 11. A stand 12 secured to and extending laterally from the loom frame 11 has guided for vertical motion therein a block 13 which is reciprocated by mechanism not shown. Pivotaly mounted on said block is an actuator lever 14 the inner end of which is pivotally connected to a rod 15 extending to the replenishing mechanism and serving to set the latter when said rod is depressed. The outer end of the lever extends through a cap 16 secured to the stand 12 and having a vertical transverse slot 17 therein to receive the lever. Slidably mounted in said stand is a controller 18 the forward end of which is guided in the stand 12 and has secured thereto a collar 19 between which and the stand extends a light compression spring 20 tending to hold the controller rearwardly. The controller 18 is provided with a depending offset 21 guided by the stand 12 and provided with a slot 22 normally lying under and in alignment with the slot 17 of the cap. The rear end of the controller 18 has secured thereto a broadened cup 23 which is adapted to extend through a slot 24 formed in the binder B and shuttle S. The actuator may be provided with a notch 25 and the lower edge of the actuator lever 14 may be inclined to fit the notch.

So long as sufficient yarn for continued weaving is present the lever 14 will move up and down in the aligned slots 17 and 22 as the block 13 reciprocates but at the time of weft exhaustion the controller 18 will be 90 moved forwardly until the notch 25 lies under the lever 14 at which time descent of the latter is prevented and indication is given to the replenishing mechanism. With the exception of the cup 23 and the particular form of controller 18, the matter thus far described is substantially the same as the mechanism set forth in Patent No. 1,030,748.

In carrying out my improvements I provide the lay with a box back 30 having a long and narrow slot 31 therein in which is secured the correspondingly formed upper horizontal mouth 32 of an air nozzle 33. The latter is secured to the upper end of a flexible hose 34 which may have projecting 100 therethrough by means of mechanism set

forth in the aforesaid co-pending application a blast of air sufficiently strong to move the controller 18 forwardly.

The shuttle S is provided with a bobbin 5 W made substantially in the manner set forth in Patents Nos. 1,220,685 and 1,337,706. The butt 35 of the bobbin is held in place by the usual springs 36 cooperating with the rings 37 and said bobbin is provided 10 with a barrel 38 which may be either conical or cylindrical. The barrel has extending therethrough a series of holes 39 which are arranged in spaced parallel planes perpendicular to and cutting across the axis of 15 the bobbin at equally spaced points. As shown herein six holes are arranged in three spaced groups of two each, and the groups are staggered angularly with respect to each other so that any plane passing through the 20 axis of the bobbin will cut through at least one hole, irrespective of the angular position of the bobbin.

Referring to Fig. 6 where both ends of the openings are shown diagrammatically, I 25 have shown a rectangular area 40 enclosed in dotted lines and representing the cross section of the blast of air which issues from the mouth 32 against the bobbin. It will be seen that said area will embrace parts 30 of at least two of the openings 39 and as the openings are aligned in pairs it will be seen that the blast of air issuing from the mouth 32 will be able to pass through one or more of the openings and be projected 35 against cup 23.

Under normal conditions presence of sufficient weft will deflect the blast of air as indicated by the arrows in Fig. 2 so that cup 23 will be unaffected and lever 14 will be free to move downwardly in slot 22, but at the time of substantial exhaustion of weft the holes 39 will be uncovered and air will pass through one or more of them, and through the front shuttle wall and pass on 45 to the cup 23 to move the latter forwardly thus moving slot 22 out of alignment with lever 14 to give an indication of weft exhaustion as previously described. Reference to Fig. 1 will show that the cup 23 is slightly wider than the perforated part 50 of the barrel bobbin and that the mouth 32 is sufficiently wide to have air issuing therefrom pass through at least one hole when the shuttle is properly placed. It is to be 55 understood that the blast of air issues from the mouth 32 while the lay is on front center and that lever 14 has its operative downward motion at this time also.

From the foregoing it will be seen that I 60 have provided a pneumatic weft detector depending for its operation upon a passage of air through a depleted bobbin and that the

latter is so constructed as to be operatively placed irrespective of its angular position with respect to the shuttle.

65

Having thus described my invention it will be apparent that changes and modifications may be made therein by those skilled in the art without departing from the spirit and scope of the invention, and I do not wish 70 to be limited to the details herein disclosed but what I claim is:

1. In a pneumatic weft detector for a weft replenishing loom, a controller to indicate weft exhaustion and occupying one position when sufficient weft is present and occupying another position when insufficient weft is present, said controller having a surface responsive to air pressure, a bobbin having a plurality of angularly spaced air 80 passages extending transversely therethrough, and means to direct a stream of air against the bobbin and toward the responsive surface, said bobbin when supplied with sufficient weft deflecting the air away 85 from the controller and said bobbin being so formed that when insufficient weft is thereon air will reach the surface responsive to air pressure to cause said controller to occupy the position to indicate weft exhaustion, the bobbin being effective to assist in indicating weft exhaustion in all angular positions thereof.

2. In a weft detector for weft replenishing looms, a bobbin having a plurality of spaced openings extending therethrough staggered with respect to each other so that a plane passing through the axis of the bobbin will cut through at least one of the openings, and a pair of pneumatically operating 90 devices one disposed on each side of the bobbin to effect indication of weft exhaustion when the openings are sufficiently uncovered to permit a stream of gaseous fluid to pass from one of said devices to the other.

95

3. In a pneumatic weft detector for a weft replenishing loom, a controller to be moved at the time of weft exhaustion having a surface responsive to air pressure, means to project a stream of air toward the responsive 100 surface of the controller, and a bobbin interposed between the means and the surface and provided with a plurality of spaced openings extending through the bobbin and at least one of which will be in alignment 115 with the stream of air and the surface responsive to air pressure to allow air to pass toward and move the controller when said openings are uncovered by a substantially exhausted supply of weft on the bobbin.

120

In testimony whereof I have hereunto affixed my signature.

WALTER H. WAKEFIELD.
